UNITED STATES PATENT OFFICE.

BERTRAM C. TRAVIS, OF LOS ANGELES, CALIFORNIA.

PIPE-PERFORATING MACHINE.

Application filed August 27, 1923. Serial No. 659,497.

My invention relates particularly to machines for perforating pipe or casing to be used in wells, and it has among its salient objects,—to provide a machine which can be 5 operated on the inside of a pipe or casing for boring holes through the wall of said pipe or casing from the inside outwardly with means for reaming the inner ends of said holes; or, in other words, making holes 10 which are larger in diameter at the inner surface of the pipe than they are at the outer surface thereof, thus making certain that anything starting through the holes from the outside can not clog the hole but 15 will pass readily through the hole and into the pipe or casing; to provide improved means for driving the drill bit or boring tool and also for feeding it to and from the work; to provide improved means for lubricating the working parts; to provide a simple and compact tool or working head, any 20 desired number of which can be connected together and operated from a common driving shaft and a common feed shaft, said tools 25 or heads being placed together side by side on said shafts like beads on a string and operated simultaneously as one machine or device having a plurality of boring bits, said tools or heads having passageways there- 30 through which register with each other when placed together and form continuous passageways for lubricant, with feed ports to the parts needing lubrication in each head or tool; and, in general, to provide an im- 35 proved, practical and efficient machine for rapidly perforating pipe or well casing from the inside with perforations of tapering form.

In order to fully explain my invention, I 40 have illustrated one practical embodiment thereof on the accompanying sheet of drawings, which I will now describe. In the drawings,—

Figure 1 is a side elevation of a machine 45 embodying my invention, showing a pipe in section with a series of my improved perforating tools or heads in place in said pipe;

Figure 2 is a sectional view through one 50 of the tools or heads, showing the interior mechanisms for driving and feeding the drill bit;

Figure 3 is a fragmentary cross sectional 55 view longitudinally of the operating shafts, showing one tool or head and parts of two others at opposite sides, with connecting means therefor.

Referring now more in detail to the drawings, I will describe one tool or head shown for the purpose of illustrating the invention. This comprises a body member of circular 60 form, designated 1, and of a size to pass into a pipe or casing to be perforated, but in operation a series of said tools or heads are secured together for simultaneous operation and the pipe or casing is telescoped over said 65 tools, in substantially the manner indicated in Fig. 1 of the drawings. Said body member is provided with a central bore or opening 2, extending vertically therethrough. A drill bit or perforating tool, 3, is provided, 70 having the boring end 3^a, and the reaming portion 3^b, whereby as said drill bit is forced through the pipe or casing from the inside in a manner to be described, it bores a hole 75 from the inside out and then reams the inner end of said hole in a manner which will be readily understood from the drawings. Said drill bit is provided with a split bushing, 4, with a lug or key portion, 5, adapted to fit into a corresponding cavity or 80 key-seat 6, in said drill bit. Said drill bit and its bushing are inserted into the lower end of a chuck member 7, said bushing being screwed therewith and operating to lock said drill bit in place, in the manner indicated in 85 Fig. 2. Near its upper end said chuck member 7 is provided with a spiral gear, 8, keyed thereto by means of a key 9, which spiral gear, 8, meshes with a spiral gear 10, keyed as at 10^a, to a drive shaft 11, which extends 90 through any desired number of tools or heads in the manner indicated in Fig. 1. A rack bar 12, is secured to a sleeve 13, on said chuck member 7, said rack bar 12, meshing 95 with a feed gear 14, keyed to a feed shaft 15, by a key 16.

Thrust ball bearings, 17 and 18, are provided near the opposite ends of the chuck member 7. The bearings 17 operate between washer-like members 17^a and 17^b, placed 100 over said chuck body 7, as clearly shown in Fig. 2, with a closure plug 2', screwed into the top of the central bore 2, in the body member 1. The bearings 18 operate between washer-like members 18^a and 18^b, around the 105 lower end of said chuck member 7, which is enlarged, as at 7', at its lower end. A through pin, 19, is inserted through said chuck member 7, near its middle, at the upper end of the sleeve 13, and against 110 which the upper end of said sleeve 13, and said rack bar, 12, bear, in order to raise the

chuck member 7 and the drill bit 3. Self-aligning bearing rings, 20 and 20', are placed above said pin 19, and a washer 21 is placed around the drill chuck between said pin 19 and the upper ends of the sleeve 13 and the rack bar 12. Openings 22 and 23 are provided through the body member 1, and when a number of said body members are placed together side by side on said operating shafts 11 and 15, the openings 22 and 23 register with the other openings and thus form a continuous passageway through the group of heads for lubricant. From the opening 22, in each head, extends a feed port 22a, which leads to the central bore 2, above the bearing rings, 20, 20', for lubricating the spiral gears 8 and 10. From the passageway 23, a supply port 23a leads down to an inserted member 24, from which is a feed port 24a, for supplying lubricant to the drill bit at the work end. Said drill bit, 3, is a double ended bit and can be reversed end for end, as will be understood from the showing.

Referring to Fig. 3, what may be termed internal splice collars 25 and 26, are placed on the feed shaft 15 and the driving shaft 11, between the heads, 1, as they are placed together, thus more effectively interlocking and aligning them together. These alignment collars 25 and 26 are held in place, respectively, by set screws 25a and 26a. They also form abutments for the gears 10 and 14 on said shafts. In order to more firmly secure said several heads or tools together, tie rods or bolts, as 27, 28 and 29, are used through said heads.

While I have shown and described one practical embodiment of my invention, I am aware that many changes can be made in the details of construction and arrangement as here shown for illustrative purposes without departing from the real spirit of the invention, and I do not, therefore, limit my invention to the showing made except as I may be limited by the hereto appended claims.

I claim:

1. In a pipe perforating machine, a body member of cylindrical form, a drill chuck movably mounted in said body member transversely thereof, a drill bit carried by said drill chuck, a rotatable drive shaft and a rotatable feed shaft extended through said body member in parallel relationship to the axis of said body member, gear connections from said drive shaft to said drill chuck for driving the latter and the drill bit, and gear connections from the feed shaft to said drill chuck for moving the latter and said drill bit longitudinally to and from the work.

2. In a pipe perforating machine, in combination, a plurality of body members of cylindrical form, each of said body members being provided therein with a drill chuck

movable transversely of its axis, a drive shaft extended through all of said body members parallel with their axes, gear connection in each body member from said shaft to said drill chuck for driving the drill chucks simultaneously, a feed shaft extended through all of said body members in parallel relationship with said drive shaft, rack and gear connections in each body member from said feed shaft to said drill chuck for moving the latter longitudinally, a drill bit for each body member, and means for holding it in said drill chuck to operate therewith.

3. In a pipe perforating machine, in combination, a plurality of body members of cylindrical form, each of said body members being provided therein with a drill chuck movable in said body member, a drill bit carried by said drill chuck and adapted to be moved therewith to project beyond the edge of said body member, a drive shaft and a feed shaft extended in parallel relationship through said body members, and operative connections in each body member from said shafts to said drill chuck for operating all of said drill chucks simultaneously.

4. A pipe perforating machine including in combination a solid body member adapted to fit within a pipe to be perforated, said body having a passageway therethrough from one side to the other and two bores therethrough from one end to the other, bit holding and operating means movably mounted in said passageway, two parallel shafts through said bores, gear connections from one of said shafts to said bit holding and operating means for driving said bit, gear connections from the other of said shafts for feeding said bit longitudinally to and from the side of the pipe, and means in said body for directing lubricant to said drill bit.

5. A pipe perforating machine including in combination a plurality of different body members adapted to be placed side by side within a pipe, each of said body members having a drill bit operatively mounted therein transversely thereof and each of said body members having two transverse bores parallel with each other and with the axis thereof, two operating shafts through all of said body members, gear connections from one of said shafts in each of said body members for driving said drill bit, and gear connections from the other of said shafts in each of said body members for feeding said drill bits to and from the work, substantially as described.

6. A pipe perforating machine including in combination a plurality of circular body members of disc-like form adapted to be placed flatwise against each other within a pipe, each member having a transverse opening therethrough from one side to the other and each having a plurality of bores there-

through parallel with the axes thereof, a drill bit and holding and operating means in each of said transverse openings, an operating shaft through all of said body members, gear connections in each body member between said shaft and said drill bit, a feed shaft through all of said body members, gear connections in each body member between said feed shaft and said drill bit for moving the same longitudinally to and from the work, and oil feeding means common to all of said body members for feeding oil to said drill bit and said gear connections.

7. A pipe perforating mechanism which includes a plurality of individual drill holding and operating members threaded upon an operating shaft like beads, side by side, within a pipe and fitting within said pipe, an operating shaft common to all of said members, and means common to all of said members for simultaneously feeding said drill holding and operating members to and

from the side of a pipe within which they are placed.

8. A pipe perforating mechanism including a plurality of individual round drill holding and operating members, adapted to fit within a pipe to be perforated, two operating shafts parallel with each other and upon which said members are placed one against the other, one of said shafts having connections for rotating the drill holding and operating members and the other of said shafts having connections for moving in opposite directions said drill holding and operating members for feeding the drills to and from the work simultaneously, and means common to all of said members for furnishing lubricant to said drills and said operating connections.

Signed at Los Angeles, California, this 16th day of August, 1923.

BERTRAM C. TRAVIS.
